US0D1101353S

(12) United States Design Patent (10) Patent No.: US D1,101,353 S
(45) Date of Patent:  Nov. 11, 2025

(54) ADHESIVE ARTICLE FOR BREAST SUPPORT

(71) Applicant: Perky Pear Ltd, Stockport (GB)
(72) Inventor: Samantha Holt, Stockport (GB)
(73) Assignee: PERKY PEAR LTD, Stockport (GB)
() Term: 15 Years
(21) Appl. No.: 35/521,202
(22) Filed: Mar. 28, 2024

(80) Hague Agreement Data

Int. Filing Date: Mar. 28, 2024
Int. Reg. No.: DM/237377
Int. Reg. Date: Mar. 28, 2024
Int. Reg. Pub. Date: Jun. 7, 2024

(30) Foreign Application Priority Data

Nov. 30, 2023 (GB) 6329932
(51) LOC (15) Cl. 02-01
(52) U.S. Cl.
USPC D2/706
